US0D1112524S

(12) **United States Design Patent** (10) **Patent No.:** **US D1,112,524 S**
(45) **Date of Patent:** **** Feb. 10, 2026**

(54) **DOLL HOLDER**

(71) Applicant: **EPOCH COMPANY, LTD.**, Tokyo (JP)

(72) Inventor: **Ai Nakanishi**, Tokyo (JP)

(73) Assignee: **EPOCH COMPANY, LTD.**, Tokyo (JP)

(**) Term: **15 Years**

(21) Appl. No.: **29/950,089**

(22) Filed: **Jun. 30, 2024**

Related U.S. Application Data

(62) Division of application No. 29/792,999, filed on May 4, 2022, now Pat. No. Des. 1,050,283.

(74) *Attorney, Agent, or Firm* — Fitzgerald IP Law; John K Fitzgerald, Esq.

(57) **CLAIM**

The ornamental design for a doll holder as shown and described.

DESCRIPTION

FIG. 1 is a perspective view of the front, bottom, and left sides of a doll holder showing my new design;

FIG. 2 is a front view thereof;

FIG. 3 is a rear view thereof;

FIG. 4 is a top plan view thereof;

FIG. 5 is a bottom view thereof;

FIG. 6 is a right view thereof; and,

FIG. 7 is a left view thereof.

The broken lines shown are included for the purpose of illustrating portions of the article which form no part of the claimed design.

1 Claim, 7 Drawing Sheets
